[57] CLAIM

The ornamental design for a surgical clip, as shown and described.

DESCRIPTION

FIG. 1 is a side elevational view of a surgical clip showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof, in open position;

FIG. 7 is a fragmentary view taken along line 7—7 of FIG. 6 showing the teeth portion;

FIG. 8 is a side elevational view of an alternate embodiment of FIG. 1, in open position; and,

FIG. 9 is a fragmentary view taken on line 9—9 of FIG. 8 showing the teeth portion.
